UNITED STATES PATENT OFFICE.

EDWARD S. SAVAGE, OF ROCHESTER, NEW YORK, ASSIGNOR TO AMERICAN CHEMICAL MANUFACTURING & MINING COMPANY, OF ROCHESTER, NEW YORK, A CORPORATION OF NEW YORK.

SHELF-TONGS.

No. 923,376.

Specification of Letters Patent.

Patented June 1, 1909.

Application filed April 13, 1908. Serial No. 426,803.

To all whom it may concern:

Be it known that I, EDWARD S. SAVAGE, a citizen of the United States, and resident of Rochester, in the county of Monroe and 5 State of New York, have invented certain new and useful Improvements in Shelf-Tongs, of which the following is a specification.

This invention relates to shelf tongs, and 10 consists in the apparatus hereinafter described and claimed.

The object of the invention is to provide shelf tongs that are easy to adjust to the article to be lifted by one hand only, both for 15 releasing and for seizing such article.

In the drawings: Figure 1 is an elevation of a device embodying this invention, part being broken away for compactness of illustration; Fig. 2 is an enlarged elevation of a 20 portion of the device, showing the parallel-movement mechanism thereof; Fig. 3 is a vertical section through the handle and locking apparatus, showing the parts in their positions when the jaws of the device are 25 open; Fig. 4 is a view of the same parts shown in Fig. 3, but showing their positions when the jaws are closed; and Fig. 5 is a section on the staggered line 5—5 of Fig. 3.

In the drawings, 1 is a handle of any suitable material, and of any desired dimensions. Upon the upper end of the handle is a pivot support 2, to which a pair of jaws 3, 3 are pivoted on the pins or pivots 4, 4'. In the present form of the device, the jaws are on 35 the opposite sides of the head and each jaw 3 has its own pivot, and each jaw has an extension end 6 beyond the pivot, which is connected by a link 7 and a common connecting bar or wire 8 to a lever apparatus 40 that will be described below. A spring 9 is connected at one end with the links, and at the other end with the handle by a pin 10. The normal tension of this spring tends to hold the jaws open.

45 Upon the end of each jaw is pivoted a gripping piece or plate 11, having on its gripping face, if desired, a roughened or im- 50 pressible pad. The pivot pins 12 connect the gripping plate 11 with the jaw 3. To the gripping plate is also pivoted, by the pivot 13, a bar 14, which, with the jaw 3, constitutes a parallel-movement mechanism for maintaining the jaws 11 either parallel 55 to each other, or at any selected and definite angle to each other. In the present form of

the device, the faces of the gripping plates 11 are always parallel, so that the gripping faces are maintained in a fixed relative relation. The jaw 3 on one side of the apparatus is connected to the pivot 4', and to the gripping plate 11 by the pivot 12. The bar 14 is connected at one end to the pivot 4, and at the other end to the pivot 13. The pivots 12 and 13 are at the same distance apart as the pivots 4, 4', and a line passing through 60 the pivots 12 and 13 is parallel to a line passing through the pivots 4, 4'. This constitutes a well known form of parallel-movement mechanism. Hence, as the connecting rod 8 is reciprocated, and the spring 9 expands and contracts, the jaws 3, 3 approach or recede from each other, and the gripping plates 11 move with the jaws and parallel 65 to each other.

The jaw 3 may be hollow or U-shaped in 70 cross-section, and the bar 14 may lie in the hollow or U-shaped jaw 3 as shown in Fig. 2; thereby producing light and strong jaws 3, and preventing the buckling of the bar 14 75 while guiding and supporting it.

80 The handle apparatus comprises a lever 15 operating on one side of the handle 1, and having depending arms 16 straddling the handle 1 and pivoted at their lower ends by a pin 17 to a block 18 fastened on the lower 85 or opposite side of the handle 1. The lever 15 is therefore in the form of a bell-crank, and the connecting rod or wire 8 is fastened to it in any suitable way, such as by the loop 19 which passes around the handle and is 90 connected in a manner described below.

To the lever 15 is pivoted a detent 20, of a bell-crank form, by a transverse pivot 21. A spring 22 having one end resting on an 95 abutment on the lever 15, and the other end resting against one arm of the detent 20, tends to pull said detent in one direction. The loop 19 is connected to the other arm of 100 said detent, and when the lever 15 is depressed toward the handle 1, and the jaws 11 grip an object, the detent 20 is tilted and the spring 22 is compressed. Thus the detent is controlled by the gripping pressure which must overcome the spring 22.

105 Upon the lever 15 is pivoted also a pawl 24 on a transverse pivot 25, for locking the jaws in gripping position. The said pawl has a face or notch 26 for engaging an edge of the detent 20, whereby, when the said 110 jaw engages the notch, the pawl 24 is held

out of action. A spring 27 tends to move said pawl in one direction so as to maintain the engagement of the notch 26 with the detent 20. The spring 22 tends to move the 5 detent 20 into the position for holding the lock in an inoperative position. Upon the handle is fastened a ratchet rack 28, with which the pawl 24 is adapted to engage when it is allowed to operate, and the spring 27 10 moves the pawl when the latter is released, so that it engages the rack.

The operation of the device is as follows: If one desires to lift a package, book, or other article from a high shelf, the jaws are placed 15 one on each side of the article so to be lifted, and the lever 15 is tilted so as to move it toward the handle 1. This closes the jaws and gripping plates upon the article in question. The gripping piece is pivoted to the 20 jaw, and is tilted in order to maintain the parallelism above mentioned around an axis transverse to the plane of movement of the jaw, and is therefore automatically adjusted to objects grasped by the apparatus.

25 As soon as the article to be lifted is grasped by the gripping pieces and jaws, and the lever 15 is further depressed, the pull of the connecting rod 8 and loop 19 upon the detent 20 tilts the latter, compresses the spring 22 until 30 the parts take the position shown in Fig. 4, thereby causing the detent 20 to recede from the notch 26 in the pawl 24, and by the action of the spring 27, the pawl thereupon engages the rack 23 and locks the jaws in the position 35 to which they have been set. But until the selected gripping pressure is reached, which permits the compression of the spring 22, the pawl 24 remains inactive and the jaws may be opened and closed freely by the action of 40 the lever 15 and spring 9. When, however, the gripping pressure is reached, the pawl 24 automatically engages its rack, and the parts are locked in gripping position. This device, therefore, by adjustment of the spring 22, is 45 inoperative for gripping purposes until a predetermined gripping pressure is attained, but when that gripping pressure occurs, the jaw mechanism is automatically locked.

50 It is obvious that if one of the jaws becomes fixed, the other jaw will operate.

What I claim is:—

1. In a shelf tongs, the combination of a handle; jaw mechanism carried by said handle; and means for automatically locking 55 said jaw mechanism upon the occurrence of a predetermined gripping pressure.

2. In a shelf tongs, the combination of a handle; jaw mechanism carried by said handle; operating means for said jaw mechanism; and means for automatically locking 60 said operating means upon a predetermined gripping pressure of said jaw mechanism.

3. In a shelf tongs, the combination of a handle; jaw mechanism carried by said han-

dle; operating means for said jaw mechanism; a two-part locking mechanism for locking said jaw mechanism in gripping position, having one part carried by the operating means, and one part carried by the handle; a detent for preventing action of said locking mechanism; and means controlled by the gripping pressure for releasing said detent. 65

4. In a shelf tongs, the combination of a handle; jaw mechanism carried by the handle; a hand lever pivoted on the handle and connected to said jaw mechanism; a locking device carried by said lever; means on the handle for engagement with said locking device; a detent for preventing action of said locking device; and means controlled by the gripping pressure for releasing said detent. 75

5. In a shelf tongs, the combination of a handle; jaw mechanism carried by the handle; a hand lever pivoted on the handle; a 80 pawl carried by said lever; a rack on the handle for engagement with said pawl; a detent carried by said lever for preventing action of said pawl; a connection from said detent to said jaw mechanism; and a spring compressed by the pull of the connection upon 85 said detent by movement of said detent that releases said pawl.

6. In a shelf tongs, the combination of a handle; hollow jaw mechanism carried thereby; gripping pieces carried by said jaw mechanism; means lying within said hollow jaw mechanism for maintaining a fixed relative position of the gripping pieces as the jaw mechanism opens and closes; and means for 90 operating said jaw mechanism. 95

7. In a shelf tongs, the combination of a handle; hollow jaw mechanism pivoted to said handle; one or more gripping pieces pivoted to said jaw mechanism; a parallel movement bar pivoted to said handle and to each gripping piece and lying in said hollow jaw mechanism; and means for operating said jaw mechanism. 105

8. In a shelf tongs, the combination of a handle; jaw mechanism comprising a hollow movable jaw pivoted to said handle; a gripping piece pivoted to said jaw; a parallel movement bar pivoted to said handle and to said gripping piece and lying in said hollow 110 jaw; and means for operating said jaw. 115

9. In a shelf tongs, the combination of a handle; jaw mechanism, comprising a movable jaw U-shaped in cross-section and pivoted to said handle; a gripping piece pivoted 120 to said movable jaw; a parallel movement bar pivoted to said handle and to said gripping piece, and lying in the U-shaped jaw; and means for operating said movable jaw.
